United States Patent Office

Des. 209,338
Patented Nov. 21, 1967

209,338

JUG

Warren L. Price, Elizabeth, N.J., assignor to Chevron Research Company, San Francisco, Calif., a corporation of Delaware

Filed June 23, 1966, Ser. No. 2,839

Term of patent 14 years

(Cl. D58—5)

FIG. 1

FIG. 2

FIG. 3

FIG. 4

FIG. 5

FIG. 6

FIGURE 1 is a side elevational view of a jug showing my new design;

FIGURE 2 is a second side elevational view of my new design taken from a side opposite that of FIGURE 1;

FIGURE 3 is a front elevational view of my new design;

FIGURE 4 is a rear elevational view;

FIGURE 5 is a top plan view; and

FIGURE 6 is a bottom plan view.

I claim:

The ornamental design for a jug, substantially as shown.
